FLOW-CONTROLLED VALVE

Parke H. Thompson, Millville, N. J., assignor of
thirty-five per cent to Russell Maguire, New
York, N. Y.

Application May 8, 1939, Serial No. 272,375

24 Claims. (Cl. 62—127)

This invention relates generally to valves and, more particularly, to a certain new and useful improvement in flow-controlled valves adapted particularly for use in connection with refrigerating systems and the like.

My invention has for its primary objects the provision of a control valve of the type stated, which is simple in construction and economical in operation and maintenance, which may be readily designed as a complete unitary structure, which is uniquely responsive to a function of the system which it controls so as to achieve and maintain an extremely high efficiency in the system regardless of design or load conditions, which is automatically compensated for overtravel, which is adapted to extract any liquefied portions of the returning fluids from the system with which it is connected and reintroduce such separated liquid into the system with the incoming supply of fluid over which control is being maintained, and which is highly efficient in the performance of its intended functions.

And with the above and other objects in view, my invention resides in the novel features of form, construction, arrangement, and combination of parts presently described and pointed out in the claims.

In the accompanying drawing:

Figure 1 is a vertical sectional view of a fluid-flow control valve constructed in accordance with and embodying my present invention;

Figures 2 and 3 are transverse sectional views of the valve, taken approximately along the lines 2—2 and 3—3, respectively, Figure 1;

Figure 4 is a schematic view of a refrigerating system incorporating a control valve of my invention; and

Figure 5 is a fragmentary sectional view of an adjustable leak port which may be used in connection with the present invention.

Referring now more in detail and by reference characters to the drawing, A designates, in a preferred form, a control valve of my present invention. Such valve includes a cylindrical preferably metallic shell 1 open at its upper end and there provided with an annular mounting flange 2 having a plurality of internally threaded apertures 3.

At its lower end, the shell 1 is welded or otherwise hermetically sealed to an end plate 4 centrally provided with an internally threaded aperture 5 for adjustably receiving a frusto-conical nozzle 6 having an upwardly presented seat or orifice 7 and a downwardly presented diametral slot or nick 8 for facilitating nozzle-adjustment.

Welded or otherwise fixed upon the outer or under face of the end plate 4 in registration with the aperture 5, is a connection collar 9 for conventional hermetically sealed engagement with the connection flange 10 of a supply line 11, all as best seen in Figures 1 and 3 and for purposes presently more fully appearing.

Welded or otherwise fixed upon the inner face of the shell 1 a short distance downwardly from the upper margin thereof, is an annular series of suitably spaced blocks 12 for supporting engagement with an annular plate 13 having an external diametral size substantially equivalent to that of the shell 1 and forming with the shell 1 an enclosed sump chamber a, the plate 13 being of sufficient thickness to project a substantial distance above the upper margin of the shell 1, all as best seen in Figure 1 and for purposes more fully presently appearing.

Adjacent its periphery, the plate 13 is apertured, as at 14, and centrally on its under face has a shallow annular recess, as at 15, of relatively large diameter, as shown. The plate 13 also has a central valve stem accommodating aperture 16, while surrounding the recess 15, the plate 13 has an annular series of stud accommodating apertures 17, all as best seen in Figures 1 and 3, and for purposes presently fully appearing.

Disposed on the under face of the plate 13, is a diaphragm 18, which extends over the recess 15 in the formation of an actuating or pressure chamber b, the diaphragm 18 having a plurality of apertures 19 in registration with the apertures 17 and a central aperture 20 substantially larger and in axial alignment with the aperture 16.

Disposed upon the under face of, and in peripheral registration with, the diaphragm 18, is a sealing ring 21 having a plurality of internally threaded recesses 22 in registration with the apertures 17, 19, for receiving stud-bolts 23, which latter extend through the apertures 17, 19, into the recesses 22 and draw the ring 21 toward the plate 13 for tightly sealing the diaphragm 18 therebetween.

Formed integrally with, and suspended from, the sealing ring 21, is a frusto-conical or cupped plate 24 centrally provided with a valve stem accommodating guide aperture 25 in registering alignment with the base aperture 16, the plate 24 being also provided in the wall of the aperture with an annular series of slots, as at 26, opening to the opposite faces of the plate 24 for providing free or open communication between the chamber a and the under side of the diaphragm 18.

Mounted concentrically within the recess 15

upon the upper face of the diaphragm 18, is an upper pressure plate 21 having a concentric hub 28 sized to snugly fit the enlarged diaphragm aperture 20 for engagement with a second or lower pressure plate 30 mounted on the under face of the diaphragm 18 in concentric alignment with the upper pressure plate 27, the bore of the hub 28 being in registration with the aperture 16 of the plate 13 and the pressure plate 30 providing an abutment for the upper end of a compression spring 31 impingingly seated at its other end in an annular channel 32 in the cup-like member 24, all as best seen in Figure 1 and for purposes presently appearing.

The shell 1 is preferably provided with an outlet aperture 33 and an external registering connection collar 34 for conventional engagement with the flanged end 35 of the outlet line 36, all as best seen in Figure 1 and for purposes presently more fully appearing.

Welded or otherwise fixed, as at 29, upon the under face of the cup-like member 24, is an elbow tube 37 terminating at its upper end in substantially flush alignment with an outlet aperture 33 formed in the shell 1 and at its other end in a plane spaced a short distance above the orifice 7, the tube 37 in its lower end portion being provided with an annular insert-sleeve 39 internally bored in the provision of a Venturi-constriction 40.

In its side wall, the tube 37 is provided with a valve stem accommodating aperture 41 also in registering alignment with the valve stem accommodating aperture 16 of the plate 13, all as best seen in Figure 1 and for purposes presently appearing.

Welded or otherwise fixed in the hub 28 for shiftable movement with the pressure plate 27, is a tubular valve stem 42 extending upwardly through the recess 15 and shiftable through the aperture 16 of the plate 13 and downwardly through the aperture 25 of the plate 24 and the aperture 41 of the elbow tube 37 and axially through the Venturi-constriction 40 and orifice 7, the stem 42 being provided on its lower end with an annular nozzle engaging ring 43.

The stem 42 is further provided with two longitudinally spaced pairs of diametrically opposed apertures 44, 45, disposed on respectively opposite sides of the base plate 13. Fixed within the stem 42 and spaced downwardly from the lowermost pair of apertures 44, is an annular seat-forming collar 46 for accommodating the reduced end of a valve-pin 47 shiftable mounted in, and projecting at its upper extremity outwardly from the upper end of, the valve stem 42.

Fixed above the uppermost pair of apertures 45 upon, and extending obliquely across, the upper end of the valve stem 42, is a fulcrum plate 48 having an upwardly presented acuminate or knife-edge 49 spaced laterally a short distance from the axial center line of the valve-pin 47, all as best seen in Figure 1 and for purposes presently more fully appearing.

Welded or otherwise fixed upon the upper face of the plate 13 adjacent its outer periphery, is an upwardly extending channel-shaped support member 50 provided at its extremity with a pivot or hinge pin 51, swingably mounted upon which is a pair of links 52 arcuated or bowed outwardly and brought together at their outer ends for pivotal connection with a pin 53 mounted at its ends in and extending between a pair of short inwardly projecting ears 54 welded or otherwise

fixed upon the inner face of a suitable catch-bucket 55 provided in its side wall with a drain aperture 56 so positioned and sized as to permit the liquid contents of the bucket 55 to drain therefrom at a predetermined rate.

On its under face, the bucket 55 is provided with a pair of laterally spaced downwardly projecting ears 57 for pivotal connection with the outer end of a counterbalancing lever 58, which, at its inner end, rests upon the upper end of the valve-pin 47 and the knife-edge 49 of the fulcrum plate 48.

Riveted or otherwise fixed on, and extending as a continuation beyond the inner end of, the lever 58, is a counterbalancing leaf spring 59 deflected downwardly at its free end and adjustably held in such deflected position between a pair of clamp nuts 60, 61, threadedly disposed upon a vertical stud 62, which is, in turn, mounted at its lower end in the plate 13.

Adjacent its upper margin and opposite the supporting member 50, the cup 55 is cut away in the formation of a U-shaped clearance slot 63 in a more or less conventional manner, so that the cup 55 will not strike against the supporting links 52 and interfere with its own swinging vertical movement, all as best seen in Figures 1 and 2 and for purposes more fully appearing.

Mounted in snug fitting annular engagement around the upwardly projecting portion of the base plate 13 and registering endwise with the shell 1, is a cylindrical cap 64 provided at or adjacent its lower margin with an external annular flange 65 machined for complementary seating engagement with the shell flange 2 and having a plurality of apertures, as at 66, for accommodating attachment bolts 67 threadedly engaging the flange 2 at the apertures 3 for drawing the cap 64 and shell 1 into tight hermetically sealed engagement. As also seen in Figure 1, the cap 64 is further provided at its upper end with a rounded or dome-shaped end wall 68 centrally provided with an aperture 69.

Welded or otherwise fixed in hermetically sealed relationship upon the upper face of the end wall 68 in registration with the aperture 69, is a preferably conical connection fitting 70 provided upon its inclined faces with a pair of more or less diametrically opposed apertures 71, 72, for communication, respectively, with conventionally mounted return and suction lines 73 and 74.

Welded or otherwise fixed in the aperture 72 of, and extending axially downwardly and inwardly from, the fitting 70, is a thin-walled tube 75 diametrically enlarged and presented downwardly in the provision of an inner cylindrical baffle 76 disposed concentrically within the cap 64 and downwardly into the catch-bucket 55.

Similarly welded or otherwise fixed to and upon the under face of the end wall 68 of the cap 64 in marginal registration with the aperture 69, is an outer cylindrical baffle 78 also extending concentrically downwardly into the interior of the cap 64 and terminating inside of the catch-bucket 55 in a plane preferably spaced slightly upwardly from the plane of the lower margin of the inner baffle wall 76.

It will be noted by reference to Figures 1 and 2 that the inner baffle 76 and its associated tube 75 are substantially smaller in diametral size than the outer baffle 78, so as to provide an outer chamber 79 having communication with the return line 73 and an inner chamber 80 having communication with the suction line 74.

Mounted at their ends upon, and extending radially between, the baffles 76 and 78, and positioned preferably adjacent the lower extremity of the baffle 78, is a series of downwardly deflected vanes 81, all as best seen in Figures 1 and 2 and for purposes presently fully appearing.

Although the control valve of my present invention may be employed in a wide variety of different systems employing liquids under pressure, the valve A is, for purposes of explanation, here shown in connection with a more or less conventional type of refrigerating system which includes a compressor B connected to a liquid receiver C, in turn, connected to the intake or supply line 11. Connected at its intake-end to an outlet line 36, is a conventional coil-type evaporator D serving as the "point of application," so to speak, of the fluid flow being controlled by the valve, the evaporator D being, in turn, connected at its discharge end to the return line 73.

The suction line 74 of the valve A is connected through a conventional type of conduit to the suction connection of the compressor B. Initially the coil D will either be empty or only partially filled with liquid refrigerant; hence the pressure within the chamber a will be relatively low.

At the same time, the catch-bucket 55 will be substantially empty. Meanwhile the high pressure of the liquid refrigerant in the intake line 11 will be exerted through the tube-like valve stem 42 against the valve-pin 47. This pressure, in combination with the counterbalancing tension of the leaf spring 59, will force the bucket 55 upwardly and permit the pin 47 to move out of seating engagement with the seat-forming collar 46. Thereupon a small quantity of liquid refrigerant will expand through the apertures 44 into the chamber b, forcing the diaphragm 18 downwardly and compressing the spring 31. Accordingly, the entire valve stem 42 will be shifted downwardly and the valve ring 43 moved out of seating engagement with the nozzle 6, thereby allowing the high pressure liquid refrigerant of the intake 11 to expand and flow through the orifice 7 and the Venturi-constriction 40 into the elbow tube 37 and thence through the outlet pipe 36 to the evaporator D.

In the evaporator, the liquid refrigerant will expand, so that the fluid returning from the discharge side of the evaporator through the return line 73 will be partially liquid and partially gas and will, upon entering the annular chamber 79, impinge against the inclined walls of the tube 75 and take up a tangential motion, centrifugally separating the major portion of the liquid from the gas. As the gas flows downwardly across the vanes 81, a final rotatory motion thereby imparted to it will effect separation and removal 60 of the remaining liquid.

The returned liquid will drain downwardly over the side faces of the baffles 76-78 and the vanes 81 and into the catch-bucket 55. Then, as the level of the returned liquid in the bucket 55 rises above the aperture 56, the liquid will commence to flow out of the bucket at a predetermined rate and fall through the aperture 14 of the plate 13 into the lower portion of the chamber a, from which it will be drawn by the 70 suction of the Venturi-constriction 40 back into the elbow tube 37 for recirculating with the incoming supply of liquid.

At the same time, liquid-free gaseous refrigerant meanwhile reverses its direction and flows 75

upwardly through the baffle 76 and tube 75 into the suction line 74, from which it returns to the compressor B for recompression.

As soon as the evaporator temperature becomes sufficiently lowered, the ratio between the quantities of refrigerant which return in liquid and gaseous phases, respectively, will increase, so that a materially larger quantity of liquid refrigerant will flow into the catch-bucket 55. Since the rate of efflux from the bucket 55 through the aperture 56 is relatively constant, the weight of the bucket 55 will increase until the increase is sufficient to overcome the force of the counterbalancing spring 59. Thereupon, the counterbalancing arm 58 will swing downwardly, shifting the valve 47 into closer seated position, restricting the supply of high pressure evaporating refrigerant which has been entering the chamber b through the apertures 44 to hold the diaphragm 18 in downwardly disposed position against the spring 31. As this supply of refrigerant is restricted or entirely cut off, as the case may be, the gas in the chamber b will leak past the annular clearance between the aperture 16 of the plate 13 and the outer face of the valve stem 42, thus reducing the pressure in the chamber b and allowing the spring 31 to shift the diaphragm 18 and the valve stem 42 upwardly for restricting or cutting off the influx of liquid refrigerant through the orifice 7. The apertures 45 serve to vent the long seating fit of the valve pin 47 and facilitate efficient pilot action.

If desired, the chamber b may be provided with an adjustable leak port p of conventional design, as shown in Figure 5, in which case the annular leakage clearance between the aperture 16 and the valve stem 42 may be dispensed with.

In this connection, it should be noted that the fulcrum plate 48 is mounted directly on the valve stem 42 and accordingly shifts upwardly and downwardly upon opening and closing movements of the stem 42 relatively to the nozzle 6. It will also be noted that, as the fulcrum plate 48 and the knife-edge 49 thereof move downwardly, the tension creating deflection of the spring 59 is decreased, thereby reducing the amount of compensating force exerted thereby.

This has the same effect as an increase in the weight of the bucket 55. Consequently, as the valve stem 42 is shifted to open the nozzle 6, the knife-edge 49 is lowered to a certain degree, thereby making the weight of the bucket 55 momentarily more effective, so as to urge the valve-pin 47 downwardly, restricting the actuating pressure exerted in the chamber b and permitting the spring 31 to shift the valve stem 42 upwardly again toward closure position to restrict somewhat, or under extreme circumstances even entirely cut off, the inflowing liquid refrigerant from the supply line.

This produces an automatic compensating effect, which prevents so-called "wild hunting" or cycling which normally results from over-travel of the control valve. As will be understood, cycling or "wild hunting" is particularly serious in refrigerating systems where the evaporator is relatively long or large and, in fact, frequently becomes so serious as to destroy all possibility of accurate control.

In valves constructed in accordance with my invention, however, the automatic compensation which results from the shifting movement of the fulcrum 48 accurately anticipates the required degree of control long before the liquid refrigerant which has entered the evaporator in response

to a particular control position has returned to the control valve and made itself directly effective thereupon.

It will, of course, be readily understood that the operating conditions of the valve may be adjusted by increasing or decreasing the deflection of the compensating spring 59 and also by changing the size or position of the duct orifice 56. It will also be understood that a level responsive flow control of the type more particularly shown in my co-pending application Serial No. 280,720 may be substituted for the drip bucket 55, if desired.

It will also be noted that all of the moving parts of the valve are uniquely assembled upon the single base plate 13, so that the entire operating structure may be assembled in a series of convenient bench operations and bodily installed within the shell 1 and cap 64. Not only does this make possible material economy in the initial production and manufacture of the valve, but also makes it possible to repair the valve quickly and conveniently.

As has been above stated, control valves of my present invention are applicable to a wide variety of uses, such as steam boiler control, air pressure regulation in humidification apparatus, liquid-vapor phase control in oil distillation apparatus and other types of fractionating or distilling columns, as well as to refrigerating systems. Regardless of application or use, it will be evident that, by my present invention, I provide a unique control valve which is capable of serving as a flow rate metering device, thereby securing extremely high efficiency in the apparatus controlled. The control valve of my present invention furthermore serves to recirculate the unevaporated liquid which leaves the evaporator or other apparatus at the discharge side. In addition, the valve functions to separate the liquid gaseous components of the liquid discharged from the evaporator or other apparatus in an unusually efficient and satisfactory manner. Finally, valves of my invention are operated upon a relay or servo-motor principle and are automatically compensated for over-travel.

It should be understood that changes and modifications in the form, construction, arrangement, and combination of the several parts of the valve may be made and substituted for those herein shown and described without departing from the nature and principle of my invention.

Having thus described my invention, what I claim and desire to secure by Letters Patent is:

1. A valve adapted to control the flow of a supply of vaporizable liquid responsive to the rate of return of unevaporated liquid comprising a shell having a chamber, said shell having a pair of apertures opening into the chamber for passing the return flow through the chamber, first means operatively mounted in the chamber actuatable responsive to variations in rate of return flow of unevaporated liquid, valve means for controlling flow of supply liquid, and means connecting the valve means with the first means for actuation thereby.

2. A valve adapted to control the flow of a supply of vaporizable liquid to a device responsive to the rate of return of unevaporated liquid from such a device comprising a shell having upper and lower chambers, said shell having a pair of apertures opening into the upper chamber for passing the return flow through the upper chamber, a catch bucket operatively mounted in the upper chamber, means for conducting a flow of

supply liquid through the lower chamber, valve means for controlling flow of supply liquid, and means connecting the valve means with the catch bucket for actuation thereby.

3. A valve adapted to control the flow of a supply of vaporizable liquid to a device responsive to the rate of return of unevaporated liquid from such a device comprising a shell, a transverse member interiorly dividing the shell into upper and lower chambers, means for passing the return flow through the upper chamber, a catch bucket operatively mounted on the transverse member for actuation responsive to change in the rate of return flow of unevaporated liquid, means for conducting a flow of supply liquid through the lower chamber, valve means for controlling flow of supply liquid, and means connecting the valve means with the catch bucket for actuation thereby.

4. A valve adapted to control the flow of a supply of vaporizable liquid responsive to the rate of return of unevaporated liquid comprising a shell, a transverse member interiorly dividing the shell into upper and lower chambers, means for passing the return flow through the upper chamber for separation of any entrained liquid, a catch bucket operatively mounted on the transverse member for actuation responsive to change in the rate of return flow of entrained liquid, said bucket having an aperture to permit efflux of the return flow liquid caught therein and said transverse member being provided with an aperture for permitting the efflux liquid from the bucket to drain into the lower chamber, conduit means for conducting a flow of supply liquid through the lower chamber, valve means for controlling flow of supply liquid, means connecting the valve means with the catch bucket for actuation thereby, and means associated with the conduit means and communicating with the lower chamber for introducing the efflux liquid into the flow of supply liquid for recirculation.

5. A valve adapted to control the flow of supply liquid responsive to rate of flow of return liquid comprising a shell, a transverse member interiorly dividing the shell into upper and lower chambers and having an aperture for providing communication between said chambers, the shell having a pair of apertures opening into the upper chamber for passing the return flow through said upper chamber, means in the upper chamber for separating entrained liquid from the return flow, a catch bucket operatively mounted on the transverse member for receiving the separated liquid and being apertured for permitting the liquid to flow at a predetermined rate into the lower chamber through the aperture in the transverse member, means for conducting the flow of supply liquid through the lower chamber, valve means for controlling liquid flow through the lower chamber, and means connecting the valve means with the catch bucket for actuation thereby.

6. A valve adapted to control a supply flow of vaporizable liquid responsive to the rate of flow of unevaporated liquid comprising a shell, a transverse member interiorly dividing the shell into upper and lower chambers and having an aperture for providing communication between said chambers, the upper chamber having an intake port for receiving the return flow, separator means in the upper chamber for removing entrained liquid from the return flow, said upper chamber further having an outlet port for discharging the vaporized portions of the return

flow, a catch bucket operatively mounted on the transverse member for receiving the separated return liquid, said catch bucket being apertured for maintaining a normal liquid-level therein and permitting any liquid in excess of such normal liquid-level to flow onto the transverse member and through the aperture thereof into the lower chamber, means for conducting a flow of supply liquid through the lower chamber, valve means for controlling the flow of supply liquid, means connecting the valve means with the catch bucket for actuation thereby, and means in the lower chamber for introducing the return liquid into the flow of supply liquid.

7. In a device of the character described, a valve having a shiftable valve stem, pressure-actuated operating means for shifting the valve stem, means for imposing pressure on the operating means, movable actuating means for varying the pressure imposed on the operating means, and means carried by the valve stem for modifying the effective movement of the actuating means for limiting travel of the valve stem to substantially prevent false-positioning thereof.

8. In a return flow responsive valve of the character described, a shiftable valve stem, actuating means operably connected to the valve stem for opening and closing the valve, an auxiliary valve for controlling the operation of the actuating means, control means operably mounted for shiftable movement responsive to variations in the rate of return flow, a lever fulcrumed on the valve stem for transmitting movement of the control means to the auxiliary valve, and a counterbalancing leaf spring associated with the lever and adapted normally to oppose the effect of the control means upon the auxiliary valve.

9. In a return flow responsive valve of the character described, a shiftable valve stem, actuating means operably connected to the valve stem for opening and closing the valve, an auxiliary valve for controlling the operation of the actuating means, control means operably mounted for shiftable movement responsive to variations in the rate of return flow, a lever fulcrumed on the valve stem for transmitting movement of the control means to the auxiliary valve, and a counterbalancing leaf spring associated with the lever and adapted normally to oppose the effect of the control means upon the auxiliary valve, said spring being adapted to have reduced opposing effect as the fulcrum moves with the valve stem for compensating over-travel of said stem.

10. In a return flow responsive valve of the character described, a shiftable valve stem, actuating means operably connected to the valve stem for opening and closing the valve, an auxiliary valve for controlling the operation of the actuating means, control means operably mounted for shiftable movement responsive to variations in the rate of return flow, a lever operably connected to the auxiliary valve for transmitting movement of the control means to the auxiliary valve, said lever having a leaf spring extending outwardly from an end thereof for exerting upon the lever, a force in opposition to the movement of the control means and means shiftable responsive to movement of the valve stem for modifying the opposing force of the spring as the valve opens.

11. In a fluid flow controlling valve, a body having a main chamber and an auxiliary chamber, a shiftable diaphragm separating said cham-

bers, means connected to the diaphragm for controlling the flow of fluid through the valve, means for by-passing a portion of the fluid from the high-pressure side of the valve to the auxiliary chamber for actuating the diaphragm, and means for controlling the flow of diaphragm-actuating fluid into the auxiliary chamber for actuating the diaphragm to increase or decrease the flow of fluid through the valve responsive to an external demand.

12. In a fluid flow controlling valve, a body having a main chamber and an auxiliary chamber, a shiftable diaphragm separating said chambers, a seat-forming nozzle for introducing fluid into the main chamber, a fluid discharge conduit leading from the main chamber, a shiftable plug interposed between the nozzle and conduit for controlling the flow of fluid from the nozzle to the conduit, a tubular stem extending at one end through the plug into the interior of the nozzle and at its other end being fixed in and extending through the diaphragm for communication with the auxiliary chamber for conducting high-pressure fluid directly from the nozzle to the auxiliary chamber for actuation of the diaphragm, and means associated with the stem for controlling the flow of high-pressure fluid to the auxiliary chamber.

13. A valve adapted to control the flow of a supply of vaporizable liquid to a device responsive to the rate of return of unevaporated liquid from such a device comprising a shell having upper and lower chambers, said shell having a pair of apertures opening into the upper chamber for passing the return flow through the upper chamber, liquid-flow measuring means operatively mounted in the upper chamber, means for conducting a flow of supply liquid through the lower chamber, valve means for controlling flow of supply liquid, and means connecting the valve means with the liquid-flow measuring means for actuation thereby.

14. A valve structure comprising a body providing a chamber, a first inlet, a first outlet, movable throttling means for controlling the flow of liquor from said inlet to said outlet, a second inlet for introducing a mixed stream of liquid and vapor into said chamber, means in the chamber actuatable in response to changes in liquid content in the stream for operating said throttling means to control the flow of liquid from the first inlet to the first outlet, and a second outlet for the vapor component of said stream.

15. A valve structure comprising a body providing a chamber, a first inlet, a first outlet, movable throttling means for controlling the flow of liquid from said inlet to said outlet, a second inlet for introducing a mixed stream of liquid and vapor into said chamber, means in the chamber actuatable in response to fluctuations in the quantity of the liquid component of said stream for operating said throttling means to control the flow of liquid from the first inlet to the first outlet, a second outlet for the vapor component of said stream, and means for recirculating a portion of said liquid component with the liquid flowing from the first inlet to the first outlet.

16. A valve structure comprising a body providing a chamber, a first inlet, a first outlet, movable throttling means for controlling the flow of liquid from said inlet to said outlet, a second inlet for introducing a mixed stream of liquid and vapor into said chamber, means in the chamber actuatable in response to fluctuations in the

quantity of the liquid component of said stream for operating said throttling means to control the flow of liquid from the first inlet to the first outlet, a second outlet for the vapor component of said stream, and means for injecting a portion of the liquid component into the liquid flowing from the first inlet to the first outlet.

17. A valve structure comprising a body providing a chamber, a first inlet, a first outlet, movable throttling means for controlling the flow of liquid from said inlet to said outlet, a second inlet for introducing a mixed stream of liquid and vapor into said chamber, means in the chamber actuable in response to changes in liquid content in the stream for operating said throttling means to control the flow of liquid from the first inlet to the first outlet, a second outlet for the vapor component of said stream, and means for damping the movement of the throttling means.

18. A valve structure comprising a body providing a chamber, a first inlet, a first outlet, movable throttling means for controlling the flow of liquid from said inlet to said outlet, a second inlet for introducing a mixed stream of liquid and vapor into said chamber, servo-motor means in the chamber actuable in response to changes in liquid content in the stream for operating said throttling means to control the flow of liquid from the first inlet to the first outlet, and a second outlet for the vapor component of said stream.

19. A valve structure comprising a body providing a chamber, a first inlet, a first outlet, movable throttling means for controlling the flow of liquid from said inlet to said outlet, a second inlet for introducing a mixed stream of liquid and vapor into said chamber, means in the chamber actuable in response to changes in liquid content in the stream for operating said throttling means to control the flow of liquid from the first inlet to the first outlet, a second outlet for the vapor component of said stream, and means for damping the movement of the servo-motor means to substantially overcome "hunting".

20. A refrigerating system including, a compressor, a condenser, an evaporator, a supply line connecting the evaporator and condenser, a return line connected to the evaporator and compressor for conducting a mixed stream of liquid and vapor from said evaporator to said compressor and a flow controlling device interposed in both the supply and return lines, said device including a chamber, movable throttling means in the chamber for controlling the liquid flow through the supply line, means also in the chamber for removing the liquid component of said mixed stream and conducting said liquid component into the chamber, and means movable responsive to changes in the quantity of said liquid component flowing into the chamber for operating the throttling means.

21. A refrigerating system including, a compressor, a condenser, an evaporator, a supply line connecting the evaporator and condenser, a return line connected to the evaporator and compressor for conducting a mixed stream of liquid and vapor from said evaporator to said com-

pressor and a flow controlling device interposed in both the supply and return lines, said device including a chamber, movable throttling means in the chamber for controlling the liquid flow through the supply line, means also in the chamber for removing the liquid component of said mixed stream and conducting said liquid component into the chamber, means movable responsive to changes in the quantity of said liquid component flowing into the chamber for operating the throttling means, and means for recirculating a portion of said liquid component with the liquid flowing in the supply line.

22. A refrigerating system including, a compressor, a condenser, an evaporator, a supply line connecting the evaporator and condenser, a return line connected to the evaporator and compressor for conducting a mixed stream of liquid and vapor from said evaporator to said compressor and a flow controlling device interposed in both the supply and return lines, said device including a chamber, movable throttling means in the chamber for controlling the liquid flow through the supply line, means also in the chamber for removing the liquid component of said mixed stream and conducting said liquid component into the chamber, means movable responsive to changes in the quantity of said liquid component flowing into the chamber for operating the throttling means, and means for injecting a portion of the liquid component into the supply line.

23. A refrigerating system including, a compressor, a condenser, an evaporator, a supply line connecting the evaporator and condenser, a return line connected to the evaporator and compressor for conducting a mixed stream of liquid and vapor from said evaporator to said compressor and a flow controlling device interposed in both the supply and return lines, said device including a chamber, movable throttling means in the chamber for controlling the liquid flow through the supply line, means also in the chamber for removing the liquid component of said mixed stream and conducting said liquid component into the chamber, means movable responsive to changes in the quantity of said liquid component flowing into the chamber for operating the throttling means, and means for damping the movement of the throttling means.

24. A refrigerating system including, a compressor, a condenser, an evaporator, a supply line connecting the evaporator and condenser, a return line connected to the evaporator and compressor for conducting a mixed stream of liquid and vapor from said evaporator to said compressor and a flow controlling device interposed in both the supply and return lines, said device including a chamber, movable throttling means in the chamber for controlling the liquid flow through the supply line, means also in the chamber for removing the liquid component of said mixed stream and conducting said liquid component into the chamber, and servo-motor means actuable to changes in the quantity of said liquid component flowing into the chamber for operating the throttling means.
